CLAIM

The ornamental design for a bag for handheld electronic devices, as shown and described.

DESCRIPTION

FIG. 1 is a front elevation view of a first embodiment of the bag for handheld electronic devices showing my new design;

FIG. 2 is a bottom plan view thereof;

FIG. 3 is a front elevation view of a second embodiment of the bag for handheld electronic devices; and,

FIG. 4 is a bottom plan view thereof.

The broken line showing of environment in the drawings is included for the purpose of illustrating only and forms no part of the claimed design.
